This invention relates to electric switches, particularly of the type employed in association with

actuators for aircraft control devices, for automatically stopping the motor of such actuators.

An object of the invention is the provision of an automatic limit control switch limiting the linear or rotary motion of an aircraft control or other driven device at various maximum and minimum limits of travel. Another object is to

provide a readily accessible, or outside, means of adjustment for varying the limits of travel. A further object is to provide a safety means for protection of the switch against accidental over-run of the motor.

Other objects and features of the invention will appear more clearly from the following description, taken in connection with the accompanying drawings, in which

Fig. 1 is a side elevation of a rotary actuator for aircraft controls in one of its limit positions, with a cover plate removed to show a switch embodying the present invention;

Fig. 2 is a side view of the switch in an intermediate position, the guide for the sliding block being omitted;

Fig. 3 is a sectional view of the switch in the limit position opposite to the one illustrated in

Fig. 1; the slide bar and the cover plate removed;

Fig. 4 is a side elevation of the switch base showing the flexible contact, stationary contacts and guide mounted thereon, looking in the direction of the arrows 4 in Fig. 6;

Fig. 5 is a sectional view as indicated by the arrows 5 in Fig. 4;

Fig. 6 is a view of the actuator, partly in elevation and partly in section, as indicated by the irregular line 6—6 in Fig. 1;

Figs. 7 to 10 are elevational views on an enlarged scale of the switch block guide, Fig. 9 being a side elevation, Fig. 7 a plan view, and

Figs. 8 and 10 end views;

Figs. 11 and 12 are enlarged views of the switch block, Fig. 12 being a side elevation and Fig. 11 a view from the left end;

Fig. 13 is an enlarged sub-assembly view of the

switch lever with its associated supporting pin and spring, together with the sliding block and

guide, the section being taken as indicated by the

arrows 13 in Fig. 14;

Fig. 14 is a cross-section of the same sub-assembly, as indicated by the arrows 14 in Fig. 13,

looking upward as in the case of Fig. 5;

Fig. 15 is a schematic wiring diagram showing

the switch of the present invention arranged to

control a three-phase induction motor; and

Fig. 16 is a diagrammatic view showing how

the switch of the present invention may be con-

nected to the transmission in an aircraft actuator

of the linear or jack screw type.

AUGUST 11, 1948

RAYMOND J. SCHAEDELER, CLEVELAND, OHIO, ASSIGNOR

TO CHICAGO PNEUMATIC TOOL COMPANY, NEW

YORK, N. Y., A CORPORATION OF NEW JERSEY

Application July 24, 1945, Serial No. 606,771

8 Claims. (Cl. 200—47)

snap ring 46. At its front end the cam has a segmental flange 47 extending for about two-thirds of its circumference, the ends of the flange providing abutments or shoulders defining a recess therebetween.

Some of the non-rotating parts of the switch, which cooperate with the cam 45 are mounted on a fibre base plate 48 which is supported at the back of the switch case, being mounted on the vertical wall 32 but separated therefrom by a strip of insulating material 49. The base plate is secured in position by screws 51. Referring to Figs. 4 and 5 the base plate 48 has a bore 52 adapted to surround the output shaft 29 and having sufficient diameter to permit passage of the cam flange 47 through the bore. Arranged above and below the bore is a pair of stationary contacts 53 and 54 each consisting of a metal strip bent into U-shape, the web portion being riveted to the base plate 48 and the right arm being somewhat wider than the left arm. The latter arm of the stationary contact is attached to an electrical conductor 55 or 56 by soldering.

Cooperating with the stationary contacts 53 and 54 and normally engaging both of them is a resilient contact 57. The latter consists of a flat metal strip bent into U-shape with the arms arranged to extend horizontally above and below stationary contacts 53 and 54 respectively. The contact member 57 is so constructed that in its detached condition the arms thereof tend to converge toward the free end, whereas in the assembled condition the parallel arms are held under tension by engagement with the right arms of the stationary contacts 53 and 54. The mid-portion of the resilient contact 57 has an integral tab 58 riveted to the base 48 to hold the resilient contact with its arms adjacent to but slightly spaced from the base plate 48. A conductor 59 is soldered to the resilient contact 57. The conductor 59 is normally connected to both conductors 55 and 56 simultaneously, but may be disconnected therefrom by spreading the arms of the resilient contact 57 against spring pressure and away from the respective stationary contacts.

The arms of the resilient contact 57 are sprung, to break the circuit, by the action of a pair of cylindrical rollers 61, composed of insulating material. The ends of the rollers abut against the cover plate 43 and base 48 to prevent axial movement. Normally each roller is also confined against more than a slight amount of translatory movement, being adapted to engage other parts of the switch at three spaced portions of the circumference of the roller. Referring to the upper roller 61, the top of the roller underlies the resilient contact 57, and the right side lies adjacent to the abutting end of an adjusting screw 62 extending through the peripheral wall of the switch case. The screw is secured in adjusted position by a lock nut 63. Near the bottom and toward the left the roller lies adjacent the inclined surface of a sliding block 64. When viewed as in Figs. 1, 2, 3, 12 and 13, the block has the shape of an isosceles trapezoid with its largest side on the left. The lower roller 61 is similarly or conversely arranged with relation to the slide block 64, resilient contact 57 and lower adjusting screw 62. The block is guided, by means to be described later, for movement vertically or transversely to the arms of the resilient contact 57. As it moves up it exerts a force on the roller 61 in a direction perpendicular to the inclined upper face of the block, that is, upwardly and to the

right. The adjusting screw limits the movement to the right, while the resilient contact resists upward movement of the roller upon becoming engaged by the latter. Upon downward movement of the block, the lower roller is urged downwardly and to the right.

In order to restrain the block 64 for rectilinear vertical movement, a guide 65 is provided. The guide is generally channel shaped, comprising a mid-portion which is riveted to the base 48 and a pair of vertical arms which slidably receive the block therebetween. The left arm is made longer than the right arm as it engages the long side of the block 64 and sustains the reactive thrust exerted on the block by the rollers 61. The right arm, however, is thicker than the left and is apertured to receive a pin 66 which extends horizontally through the guide 65, past the base 48 and insulating strip 49, and into the vertical wall 32 which defines the back of the switch case. Upon the pin is fulcrumed a lever or trigger 67, which consists of a flat stamping having a butt end on its right side near the fulcrum and having a reduced portion 68 at its opposite end. The lever swings within vertical slots 69 and 71 provided in the left and right arms respectively of the channel guide 65. The reduced end 68 of the lever projects into the recess in the segmental flange 47 on cam 45, whereby the lever may be lifted as the cam approaches the limit position of Fig. 1, or depressed as the cam approaches the opposite limit position of Fig. 3. The lever is biased toward its normal or central position by means of a flat leaf spring 72 having one arm engaging the butt end of lever 67 and the other arm resting against a recessed portion of the peripheral wall 19 of the switch case. As the lever is lifted or depressed it raises or lowers the sliding block 64. To this end the block is provided with a slot or groove 73, the side walls of which provide a bearing for an enlarged rounded portion 74 on lever 67. Toward the left end the block slot 73 is flared or enlarged to provide clearance for the lever 67 as the latter oscillates.

In operation the motor shaft 21 transmits power through the reduction gearing 23, 25, 34, etc., to drive the output shaft 29 together with the lever arm 37 which is splined thereto. Assuming that the device to be actuated occupies the position shown in broken lines in Fig. 1, the arm 37 revolves counterclockwise, moving the air control flap 41 to closed position. At the same time the cam 45 turns counterclockwise but without any immediate effect upon the other parts of the switch as the resilient contact 57 remains in engagement with the stationary contacts 53 and 54. Referring to the wiring diagram of Fig. 15 current flows from a battery wire 75 through upper set of contacts of manual switch 76, conductor 77, forward motion relay 78, conductor 55, upper stationary contact 53, resilient contact 57 and conductor 59 to ground. The relay 78 being energized, acts through its armatures to connect the motor 20 through a set of conductors 81 to a source of three-phase current 82.

The motor continues to drive the output shaft 29 until the lever arm 37 approaches the full line position of Fig. 1. Up to this time the cam 45 has been turning with lost motion relative to the lever 67 projecting within the recess in the cam. Upon approach of the limit position, however, the abutment at one end of the segmental flange 47 engages the projecting end 68 of lever 67, lifting the lever about the pivot pin 66, which in turn lifts the sliding block 64 in the channel guide

65. The inclined upper face of the block pushes the cylindrical roller 61 upwardly and toward the right. As the cam 45 continues to turn counterclockwise, and the lever 67 clockwise, and as the sliding block 64 continues to rise, the upper roller 61 becomes positively arrested against any further movement to the right due to engagement with the butt end of upper adjusting screw 62. The roller therefore presses upwardly against the upper arm of resilient contact 57. When the upward pressure of the roller against the resilient contact is sufficient to overcome the initial tension on the latter, the upper arm of the resilient contact is lifted out of engagement with the upper stationary contact 53. This breaks the circuit extending through the winding of the relay 78, which immediately releases its armatures to cut off the supply of current to the motor 20, whereupon all further movement of the rotating parts is arrested.

It should be understood that the power supply to the motor is not immediately disconnected after the cam has rotated through an arc corresponding to the length of the recess, when the segmental flange 47 strikes the projecting end 68 of lever 67. In accordance with this invention, the motor is permitted to continue operating for a considerable time after the lever 67 and sliding block 64 start to rise. The extent of such continued rotation depends upon the amount of space between the roller 61 and the three parts which engage its periphery, namely the resilient contact 57, adjusting screw 62 and sliding block 64. The extent of confinement of the roller can be regulated by turning the adjusting screw 62.

Assuming that the operator desires to open the air control flap 41, he manipulates the switch 16 to engage the lower set of contacts. Current then flows from battery wire 75 through lower set of contacts of manual switch 16, conductor 83, reverse relay 84, conductor 56, lower contact 54, resilient contact 57 and conductor 59 to ground. On becoming energized, relay 84 attracts its armatures to close a circuit which connects the motor 20 through a set of conductors 86 to the source of three-phase current 82. The motor will turn in the reverse direction, moving the cam 45 from the position shown in Fig. 1 toward the neutral position of Fig. 2. As soon as the segmental flange 47 on the cam moves out of engagement with the lever 67, the leaf spring 72 restores the lever to normal or horizontal position, whereupon the upper set of contacts 53, 57 again become engaged to permit the motor to turn forwardly on the next operation. Upon continued rotation of cam 45 toward the Fig. 3 position, the segmental flange 47 strikes the lever 67, thereby rocking the lever counterclockwise and moving the sliding block 64 and lower roller 61 downward to break the lower set of contacts 54, 57 and stop the motor.

The operator determines by observation whether the stroke of the actuator is too long or too short. If a considerably longer stroke is desired, he may conveniently remove the cover plate 43 and snap ring 46 to replace the cam 45 by another cam which has a longer recess between the abutments which define the ends of the segmental flange 47. If the actuator tends to move the control device too far in one direction and not far enough in the other direction, the operator may alter the relation between the lever arm 31 and the output shaft 29. For finer adjustment of the limit position at the end of one stroke, independently of adjustment for the opposite stroke, the

operator turns the adjusting screw 62. To lengthen the forward or closing stroke, the upper screw 62 is turned to the left, as in Fig. 1, to permit a greater amount of lost motion of the sliding block and roller 61 relative to the resilient contact 57 before the upper set of contacts is broken. The exposed heads of the screws 62, being on the outside of the housing 19, provide a ready and convenient means of adjustment of the stroke of the actuator without necessitating the removal of the cover plate 43.

If for any reason the motor and the parts actuated thereby should continue to coast beyond the position at which the switch circuit is opened, no damage to the switch will result for the reason that there is sufficient clearance to permit the lever 67 to ride over the cylindrical surface of the segmental flange 47. When out of engagement with the cam flange 47, the lever 67 is held in neutral position by spring 72 so that the cam abutments will always engage the lever without jamming.

Fig. 16 discloses a transmission which adapts the switch of the present invention for use in an actuator of the linear or jack screw type, where the output shaft of the actuator rotates through a considerable number of complete turns, instead of through a limited arc as in the case of the rotary actuator illustrated in Fig. 1. In the modification the cam 45 is mounted on a shaft 87 to which is attached a worm wheel 88. The worm wheel is driven by a worm gear 89 rigidly connected to a pinion 91 driven by gear 92 which is keyed to a jack screw 93. The jack screw may be driven by any suitable means such as reduction gearing 94 and a motor (not shown). As the jack screw rotates through the usual number of revolutions required to move the actuated device from one extreme position to the other, worm wheel 88 turns proportionately but only moves through a limited arc comparable to the movement of the output shaft and cam in the rotary actuator shown in Fig. 1.

While the invention has been described with particular relation to a specific form of rotary actuator and to a modification in which a jack screw is employed, it is to be understood that the invention is of very general application to aircraft actuators and other devices which employ a power shaft moving through a predetermined number of degrees or a predetermined number of revolutions. The invention moreover is not limited to electric motors but could be adapted to a fluid pressure motor by arranging the relays 78 and 84 to control a solenoid valve instead of connecting the motor to a source of electric power.

The terms upper, lower, horizontal, etc., appearing in the specification or claims are used in a relative, and not in a limiting, sense as the gear case 19 need not be mounted upon a vertical wall but may be supported in any desired position.

What is claimed is:

1. An electric switch comprising an oscillatory cam having a circumferential recess between two spaced shoulders, a lever having a portion extending into the recess, the lever being fulcrumed about an axis parallel to the axis of the cam, resilient means biasing the lever toward a normal position radially of the cam, a sliding block associated with the lever for reciprocal movement thereby, said block having a central slot therein through which the lever extends, a guide for restraining the block to move tangentially relative to the cam, said guide having a central slot therein through which the lever extends, and means

responsive to movement of the block away from normal position to actuate a contact member.

2. An electric switch according to claim 1 in which the last mentioned means has an adjustable amount of lost motion to vary the extent of movement of the cam, lever and block required for the actuation of the contact member.

3. An electric switch comprising a non-conductive base plate, upper and lower stationary contacts mounted on the base plate, a resilient contact having approximately parallel horizontal arms normally tensioned apart by engagement with the stationary contacts, and means for selectively forcing the arms farther part under additional tension to disengage the stationary contacts, said means comprising a cam positioned between said arms to rotate on an axis perpendicular to the base plate, a pair of circumferentially spaced abutments on the cam, a trigger positioned between the abutments and engageable thereby upon predetermined movement of the cam in either direction, a sliding block mounted to move transversely to the parallel arms near the free ends thereof, the block being movable vertically by the trigger and being arranged to force the resilient contact out of engagement with the stationary contact upon predetermined movement of the block.

4. In an electric switch, a case having front and rear walls, a horizontal shaft extending through the rear wall, a cam mounted on the shaft, a guide supported on the rear wall and having a channel open at its front end and extending vertically and tangentially to the cam, a block slidably mounted in the channel guide, a contact member extending horizontally and above the block, the upper end of the block having an inclined surface extending downwardly and toward a peripheral wall of the switch case, a roller interposed between the sliding block and contact member, a stop means supported by said peripheral wall for limiting movement of the roller toward the latter, said stop means, contact member and block normally being sufficiently spaced to permit a predetermined amount of upward lost motion of the block before the roller is simultaneously engaged by the block and the contact member and the stop means, following which lost motion the continued upward movement of the block is transmitted to the contact member for raising it from its normal position.

5. An electric switch according to claim 4 in which the stop means is adjustable toward and away from the peripheral wall to regulate the extent of lost motion, and is connected to a manipulative adjusting screw extending through the peripheral wall, whereby adjustment may be effected without opening the switch case.

6. In an electric switch, a case having front and rear walls and a peripheral wall, a horizontal shaft extending through the rear wall, a cam enclosed within the case and mounted on the shaft, a block slidably mounted for vertical movement in the case and actuated by the cam, a contact member in the case extending horizontally above the guide block, a floating element interposed between the sliding block and contact member, a stop means supported adjacent said peripheral wall for limiting lost motion of the floating element, said stop means being adjustable to regulate the extent of lost motion, and a manipulative adjusting screw extending through the pe-

ripheral wall and operatively connected to the stop means, whereby the switch may be adjusted without opening the switch case.

7. An electric switch comprising a casing, an output shaft rotatable therein without interruption to a limit position in either direction, a cam rotatable with said shaft and having a circumferential flange recessed to provide spaced abutments at opposite ends of the recess, a lever pivotally supported in the casing and positioned to be reciprocably actuated by said abutments, resilient means biasing the lever toward a normal position radially of the cam, a sliding block adapted to be moved in opposite directions by the reciprocal lever, a guide for restraining the block to move tangentially relative to the cam, a U-shaped resilient contact member the arms of which extend beyond the zone of movement of the sliding block and transverse to the direction of movement thereof, stationary members arranged in contact with the U-shaped contact member, a floating non-metallic roller at each end of the sliding block adapted to transmit force from the block to the U-shaped contact member sufficient to move the U-shaped member out of contact with the stationary members, and a screw extending through the casing adapted to adjust the position of the floating roller or rollers relative to the sliding block to predetermine the lost motion between said block and contact member and hence the amount of movement of the lever required to modify the electric current.

8. A limit switch comprising a switch case, a cam supported therein for rotary movement proportionately to a power shaft, a segmental flange on the cam forming a circumferential recess between two spaced abutments, a lever pivotally mounted in the switch case and having a projecting portion extending into the cam recess thereby being operable by one of said shoulders following a predetermined rotation of the cam, the lever being biased toward a normal position radially of the cam, and means responsive to a predetermined deflection of the lever away from normal position for modifying an electric circuit, said means comprising a sliding block actuated by the lever, a U-shaped resilient contact member having parallel arms extending on opposite sides of the block and transverse to the direction of movement thereof, a non-metallic roller at each end of the block adapted to transmit force from the block to the contact member, and means for adjusting the position of a roller or rollers relative to the block to vary the lost motion between the block and contact member and hence the amount of movement of the cam and lever required for modifying the electric circuit.
